UNITED STATES PATENT OFFICE.

THOMAS I. PORTER, OF CHICAGO, ILLINOIS, ASSIGNOR TO PORTER COUNTERFEIT DETECTOR COMPANY, OF CHICAGO, ILLINOIS, A CORPORATION OF ILLINOIS.

METHOD OF DETECTING COUNTERFEIT ARTICLES.

1,198,053.

Specification of Letters Patent. Patented Sept. 12, 1916.

Application filed April 6, 1915. Serial No. 19,612.

To all whom it may concern:

Be it known that I, THOMAS I. PORTER, a citizen of the United States, residing at Chicago, in the county of Cook and State 5 of Illinois, have invented a new and useful Improvement in Methods of Detecting Counterfeit Articles, of which the following is a specification.

My invention relates to a novel method 10 by which the genuineness of paper money, coins, certificates, bonds, postage and revenue stamps, or other articles bearing designs of any kind whether engraved, embossed, lithographed or otherwise produced thereon, 15 may be determined.

Counterfeit paper money, bonds, certificates, postage and revenue stamps, or the like, are usually made by a process involving as a step the photographing of the 20 article to be counterfeited, and while the article produced thereby may so closely imitate the original that one examining it by the methods commonly employed is deceived as to its genuineness, certain portions of 25 the photographed design on the article, do not, by reason of the distortions produced in the photographing process, occupy the same positions relative to other portions of the design thereof, as do the corresponding 30 portions in the case of the original. Furthermore a straight border line or straight line of letters is oftentimes so distorted in the photographing process that such lines on the counterfeit article will be in slanting 35 or curved position instead of straight. In the production of counterfeit coins by dies cut in simulation of the originals, the coins produced therefrom while bearing a close resemblance to the originals, nevertheless 40 present variations in relative positions of the features of the design one to another.

My primary object is to provide a method whereby the genuineness of articles of the varieties above stated may be quickly and 45 accurately determined.

In the accompanying drawing I have shown a device of a character adapted to be employed in carrying out my method particularly where it is desired to determine 50 the genuineness of paper money, Figure 1 of the drawing representing the device by a face view thereof, with two sheets of paper representing bills or notes to be compared, assembled therewith and bearing an arbi-

trary design to illustrate the manner of 55 using the device for detecting irregularities in the design of the one as compared with the other; and Fig. 2 being a section taken on the line 2—2 on Fig. 1 and viewed in the direction of the arrow. 60

In carrying out my invention I prefer to use a plate 3 of transparent material, preferably glass, with parallel lines *x* extending across its face from one edge thereof to the opposite edge and parallel lines *y* extending from one to the other of the other edges of the plate, the lines *x* and *y* being uniformly spaced and arranged at 90° to each other, as represented, to cause the glass to present a checkered appearance, each one 70 of the squares thus produced being preferably of the same area, one-quarter inch square. These lines may be formed on, or in, the plate 3 in any suitable manner (as for example by diamond ruling) so long 75 as they can be seen by the observer when the plate is positioned over the article to be compared.

The plate 3 in the construction illustrated is used in connection with a frame which, as 80 to its general features of construction, is the same as the printing frames commonly employed by photographers and involving a frame section 4 provided centrally with an opening 5, with a continuous shoulder 6 extending about the opening 5 and against which the plate 3, inserted into the frame 4 from the rear side thereof, bears, and a follower 7 adapted to fit the interior of the frame 4 and be releasably secured in position 85 as by spring clips 8, one only of which is shown, pivoted between their ends as indicated at 9, and adapted to enter grooves 10 in the side of the frame 4 by swinging the clips at their pivots and while holding 90 them with their ends pressed toward the follower 7.

By preference the face of the frame 4 is provided with extensions *y'* of the lines *y*, the spaces between these lines being marked 100 from 1 to 28 inclusive, as shown in Fig. 1. The face of the frame 4 also is provided with lines *x'* which form continuations of the lines *x*, the spaces between the first thirteen of the lines *x'* being marked A to L 105 inclusive, and the spaces between the next thirteen lines exclusive of one space, being similarly marked.

In the use of the device the articles to be compared, such as the bills or notes, are positioned between the rear side of the plate 3 and the follower 7. It is desired that the 5 upper bill indicated at 12, and which we will assume is an original bill, be so positioned in the frame that the exact center of the design thereon, and which in the case of a bank-bill or note would be a point mid-way of the ends of the border of the design, 10 register with the one of the lines y in line with the line y' which separates the spaces 14 and 15, and that the top of the design on the bill 12 register with the line x^1 defining 15 the top space A of the upper series of letter spaces. The bill or note which we will assume is a counterfeit and which is to be compared with the bill 12, is represented at 20 13, and would be so positioned that the center of the design thereon will register with the one of the lines y^1 which separates the spaces 14 and 15, and the upper line of its border will register with the line x^1 immediately above the letter A of the second 25 series thereof.

With the original bill 12 and the one sought to be compared therewith and the genuineness of which is in dispute, namely, the one represented at 13, in position as 30 stated, the operator may by means of the lines x and y readily determine, by comparing the positions of features of the design on the bills relative to these lines, whether or not the bill is genuine.

35 It may happen that while the upper portion of the design of a counterfeit bill is the same as the outer portion of an original bill, the distortion produced in the photographing process hereinbefore referred to will cause portions of the design intermediate its edges to occupy a different position relative to the border or other portions of the design in the case of the counterfeit than they do in the case of the original. 40 Thus in the illustration presented in the drawing it will be noted that the letter C and the numeral 2 appearing on the face of each of the bills 12 and 13 are somewhat closer together in the case of the bill 13 than 45 in the case of the bill 12 and tip slightly toward the center of the bill, and further, the scroll beneath the said letter and numeral presents slightly greater curvature lengthwise of the bill in the case of the counterfeit 50 than in the case of the original. Furthermore the letter and numeral referred to, and the scroll, as also the phrase "Issue of 1914," 55 occupy different positions relative to the lines which define the spaces A to L inclusive in the case of the counterfeit 13 than in the case of the original 12. The above description 60 will serve to clearly indicate the way in which my improved method may be employed to detect a counterfeit bill. It will be noted that by this method exceedingly slight

variations, immediately stamping the bill or other document as a counterfeit, may be detected by locating the features of the bill 12 relative to the intersecting lines superposed thereon, with the position of corresponding features of the counterfeit bill 13 relative to the similar lines superposing it. 70

It will be readily understood that by standardizing the spacing of the intersecting lines and the positioning relative thereto of the articles to be compared one to the other, the Government in sending out descriptions of counterfeit money to enable those handling money to more readily detect

75 counterfeits, may describe the same by stating in which space or where in a designated space, a certain feature of the design of a counterfeit bill will be found, thus enabling one desiring to determine the genuineness of a bill, by merely positioning the bill in the 80 position of the bill 13 in the construction illustrated, to readily locate the position of such feature and thereby determine the genuineness of the bill. As for example, let it be assumed that the letter C represents a feature of a bill. It will be noted that the ends of the C lie in the space D⁸ and that the line between spaces 7 and 8 passes substantially through the center of the letter C, whereas

85 in the case of the letter C in the bill 13 in the upper end of this letter lies in the space C⁸ and its lower end in the space D⁸, and the line between the spaces 7 and 8 cuts through this letter about a sixteenth of an inch to 90 the left of its center. Thus the counterfeit bill could be described by the Government by

95 stating that the ends of the letter C will be found in the spaces C⁸ and D⁸. Furthermore the location of the phrase "Issue 1914" in the one case as compared with the other would provide a means of informing the handlers of money as to the detection of 100 counterfeit bills. The above description is merely illustrative of the many conditions which may occur in the comparing of a 105 counterfeit with an original bill, and will serve to indicate a way in which my method 110 may be utilized.

115 It will be understood that the method may be practised in comparing any article bearing a design with one known to be an original wherein the relative locations of corresponding features on the articles differ in the case of the counterfeit. Besides being 120 applicable to paper objects, having engraved, embossed or printed matter thereon, it is equally applicable to coins where it is desired to detect a counterfeit made from a die cut in simulation of the original and in 125 which case the various features of the counterfeit die would occupy different positions relative to other features thereof than would be the case of an original, it being preferred that the lines x and y when coins are to be examined, be arranged to provide a 130

closer spacing than that described and this is also desired in connection with the examination of postage stamps.

While I have shown and described as the medium for comparing the relative positions of features on the articles to be compared, one with the other, a transparent plate provided with intersecting lines, which, however, is the preferred form of device employed, it is obvious that my improved method may be carried out by the use of dots, instead of continuous lines, on the transparent medium, or by using intersecting wires or strands mounted in a frame without a transparent plate, or if lines or dots are provided for the detecting purpose they could be arranged in circles or substantially so, one within the other, combined or uncombined with lines intersecting the circles, and the method which I claim could, therefore, be carried out by the use of any of those, as well as any other suitable agency.

What I claim and desire to secure by Letters Patent is:

1. The method of detecting counterfeit money, securities or the like bearing finely wrought designs, which consists in comparing the location or locations of one or more selected features in the design of the suspected counterfeit with the location or locations of the corresponding feature or features on a like article known to be genuine, by noting one or more points on a third object coinciding with the selected feature or features on one of the two articles under comparison, and noting the relation between the corresponding feature or features on the other article and the noted point or points on the third object, or a duplicate thereof.

2. The method of detecting counterfeit money, securities or the like bearing finely wrought designs, which consists in comparing the location or locations of one or more selected features in the design of the suspected counterfeit with the location or locations of the corresponding feature or features on a like article known to be genuine, by applying a third object to one of the two articles under comparison and noting one or more points on the third object coinciding with the selected feature or features on such article, and applying the same, or a duplicate object, to the other one of the articles

and noting the relation between the corresponding feature or features on such other article and the noted point or points on the third object.

3. The method of detecting counterfeit money, securities or the like bearing finely wrought designs, which consists in comparing the location or locations of one or more selected features in the design of the suspected counterfeit with the location or locations of the corresponding feature or features on a like article known to be genuine, by superposing on one of the two articles under comparison, a transparent plate provided with intersecting lines and noting the position of one or more selected features in the design on such article relative to said intersecting lines, and superposing on the other of said articles the same plate, or a duplicate thereof, and noting the relation between the corresponding feature or features on the other article and the noted intersecting lines on the third object.

4. The method of detecting counterfeit articles bearing designs, which consists in comparing a suspected counterfeit with a known genuine by arranging the suspected counterfeit and the known genuine in juxtaposition, placing over said suspected counterfeit and known genuine an object of a character adapting the articles beneath it to be exposed to view and presenting different portions thereof in direct opposition to said articles, each portion being provided with marks identical in number and distribution with that of the other, and the articles being so positioned in relation to the object that the marks on the latter occupy, so far as may be, the same relative position over one article as over the other, whereby the position of a selected feature or features in the design on said suspected counterfeit relative to one or more of said marks on one of the portions of said object may be compared with the position of the corresponding feature or features in the design of the known genuine relative to a corresponding mark or marks on the other portion of said object.

THOMAS I. PORTER.
